UNITED STATES PATENT OFFICE.

JOHN HAYS HAMMOND, JR., OF GLOUCESTER, MASSACHUSETTS.

MULTIPLEX METHOD AND SYSTEM FOR THE TRANSMISSION OF RADIANT ENERGY.

Application filed October 18, 1917, Serial No. 197,259. Renewed July 24, 1923.

Some of the objects of this invention are to provide an improved multiplex transmission system for radiant energy; to provide an improved multiplex receiving system for 5 radiant energy; and to provide other improvements as will appear hereinafter.

In the accompanying drawings, Fig. 1 is a diagrammatic representation of a transmission system constructed in accordance with this invention; and Fig. 2 is a diagrammatic representation of a multiplex receiving system constructed in accordance with this invention.

The transmission system shown in Fig. 1 comprises an open, aerial circuit 10 including an antenna 11 and a coil 12, through which the antenna is grounded at 13. The coil 12 forms the secondary of a step-up transformer 15, which includes a primary coil 16. The coil 16 forms part of a closed, oscillatory circuit 20, which includes a spark gap device 21 and a primary, variable condenser 22. The closed circuit 20 is arranged to be energized by means of a direct current generator 25 or other suitable source of electric current. One pole of the generator 25 is connected by a conductor 26 to one end of a choke coil 27, the other end of which is connected by a conductor 28 to one side of the variable condenser 22. The other pole of the generator 25 is connected through a variable resistance 30 to one end of a choke coil 31, the other end of which is connected by a conductor 32 to the other side of the variable condenser 22. The closed circuit 20 is adjusted in such a manner as to transfer the maximum amount of energy to the open, aerial circuit 10 which may be tuned, for instance, to 1,000,000 oscillations per second.

For selectively impressing upon the high frequency oscillations emitted by the open, aerial circuit 10, any one of a plurality of series of periodic amplitude variations having different, predetermined frequencies respectively, this invention provides a secondary frequency controller 35, which is connected across the primary, variable condenser 22 and which includes a tone circuit 36 comprising an inductance 36 and a variable, secondary condenser 37 in series therewith. This tone circuit 36, 37 may be normally tuned to any desired frequency, for instance, to 40,000 oscillations per second and acts to impress a series of periodic amplitude variations of a corresponding frequency

upon the oscillations set up in the closed circuit 20.

For modifying the periodicity of the tone circuit 36, 37 and consequently the secondary frequency of the system, the auxiliary, variable condensers 40 and 41 are connected across the secondary condenser 37 and are arranged to be controlled respectively by two keys 42 and 43, which are normally held open by two spiral springs 44 and 45. When either of these keys 42 and 43 is open, the corresponding auxiliary condenser 40 or 41 is rendered inoperative and when either of these keys is closed, the corresponding condenser 40 or 41 is rendered operative to vary the periodicity of the tone circuit 36, 37. The auxiliary condensers 40 and 41 may be arranged to modify the periodicity of the tone circuit 36, 37 in any desired manner. For instance, the arrangement may be such that when the key 42 is open and the key 43 is closed, the frequency of the oscillations in the tone circuit 36, 37, 41 will be 30,000 per second, and when the key 43 is open and the key 42 is closed, the frequency of the tone circuit 36, 37, 40 will be 25,000 per second, while when both keys are closed the frequency of the tone circuit 36, 37, 40, 41 will be 20,000 per second.

It is therefore thought to be evident that this invention provides a transmission or sending system which makes it possible to transmit from the same, open, aerial circuit a series of high frequency oscillations of, for instance, 1,000,000 per second, and to impress upon such high frequency oscillations selectively any one of a predetermined plurality of series of periodic amplitude variations having different, predetermined frequencies respectively. These series of oscillations having impressed thereon periodic amplitude variations may be received upon any suitable receiving system, for instance, on the receiving system hereinafter described.

In Fig. 2 is shown one form of multiplex, selective, receiving system constructed in accordance with this invention and which may be used in receiving oscillations from the transmission system shown in Fig. 1. The improved receiving system comprises an open, aerial circuit 100 including an antenna 101 and an inductance coil 102 through which the antenna is grounded at 103. The open circuit 100 is preferably tuned to the frequency of the received os-

cillations, for instance, to 1,000,000 oscillations per second. The inductance coil 102 forms the primary of a step-up transformer 110, which includes a coil 111 contained in a closed, oscillatory circuit 112. The circuit 112 is tuned to the frequency of the open circuit 100 and is arranged to act through a stoppage condenser 115 to control an oscillation detector 120.

10 The detector 120 may be of any well known or suitable construction. For instance, it may comprise a highly evacuated glass bulb or container 125, in which is arranged a filament 126, a grid 127, and a terminal 128. The filament 126 is arranged to be heated by a battery 130, acting through a variable resistance or rheostat 131. The detector 120 controls a circuit including a battery 135 and three coils 136, 137 and 138. Connected across these coils respectively are three, variable condensers 140, 141 and 142, which form with the coils three, closed, secondary oscillatory circuits 143, 144 and 145, which are preferably tuned respectively to three different, secondary frequencies, for instance, 30,000 cycles per second, 20,000 cycles per second, and 25,000 cycles per second, to correspond with the tuning mentioned in connection with the description of the transmission system shown in Fig. 1.

15 The three, closed, secondary, oscillatory circuits 143, 144 and 145 are inductively connected to three, closed, controlled circuits 150, 151 and 152, which include respectively three coils 153, 154 and 155 and three variable condensers 156, 157 and 158. These three controlled circuits 150, 151 and 152 are tuned respectively to the frequencies of the controlling secondary circuits 143, 144 and 145 and are arranged to act through three stoppage condensers 165, 166 and 167 to control three secondary oscillation detectors 170, 171 and 172. These secondary detectors 170, 171 and 172 may be of any suitable construction, for instance, of the same construction as the primary detector 120, and are arranged to control respectively three circuits including respectively three batteries 175, 176 and 177 and three coils 178, 179 and 180. Connected across the three coils 178, 179 and 180 are three variable condensers 185, 186 and 187 which form with the coils three, closed, oscillatory circuits 190, 191 and 192, which are each tuned to a frequency, for instance, of 1,000 cycles per second to cause the circuits to oscillate in response to a corresponding beat frequency which is set up as will appear hereinafter in the closed circuits 150, 151 and 152, controlling the three secondary detectors 170, 171 and 172.

20 The two closed circuits 190 and 191 are inductively connected to a common, closed circuit 195, which includes a coil 196 and a variable condenser 197 and is tuned to a fre-

quency, for instance, of 1,000 oscillations per second. This latter circuit is arranged to control an oscillation detector 198 constructed in any well-known or suitable manner or as hereinafter described and arranged to control a circuit containing a battery 199 and a telephone 200 or other receiving instrument or device.

25 The two circuits 191 and 192 are inductively connected to a common, closed, oscillatory circuit 205, which includes a coil 206 and a variable condenser 207 and is arranged to control an oscillation detector 208, constructed in any well-known or suitable manner or as hereinafter described and arranged to control a circuit including a battery 209 and a telephone 210 or other receiving instrument or device.

30 For producing electrical beats having a frequency of, for instance, 1,000 cycles per second in each of the closed circuits 150, 151 and 152 which control the secondary detectors 170, 171 and 172 any suitable means may be provided for instance, three local sources of oscillations 215, 216 and 217 of well-known construction may be provided for this purpose. These local sources of oscillations comprise respectively three oscillatory circuits 218, 219 and 220 which are arranged to be controlled respectively by three thermionic valves 221, 222 and 223 acting respectively through three batteries 224, 225 and 226. Each of the three closed circuits 218, 219 and 220 is tuned to oscillate either at a frequency 1,000 oscillations per second above or 1,000 oscillations per second below the frequency of oscillation of the corresponding, closed, control circuit 150, 151 or 152. For instance, the closed circuit 218 may be tuned to oscillate either at 29,000 or 31,000 cycles per second, and the closed circuit 219 may be tuned to oscillate either at 19,000 or 21,000 cycles per second, while the third closed circuit 220 may be tuned to oscillate either at 24,000 or 26,000 cycles per second. These three closed circuits 218, 219 or 220 are connected respectively with the corresponding control circuits 150, 151 and 152, through three electrostatic couplings 230, 231 and 232 containing respectively three variable condensers 233, 234 and 235.

35 In the operation of the receiving system shown in Fig. 2 with the transmission system shown in Fig. 1, when both keys 42 and 43 of the transmission system are open, the transmission system will emit a series of oscillations having, for instance, a frequency of 1,000,000 oscillations per second and having impressed thereon a secondary frequency or series of periodic amplitude variations of, for instance, 40,000 cycles per second. This series of oscillations will affect the open aerial circuit 100 and the primary detector 120 but will not build up oscillations in any

of the secondary closed circuits 143, 144 and 145, and therefore will not affect any of the secondary detectors 170, 171 and 172 or the telephones 200 and 210. But these oscillations will serve to confuse any operator who attempts to "listen in" upon the system and will also act to increase the efficiency and responsiveness of the transmission system.

When it is desired to control the telephone receiver 210 of the receiving system of Fig. 2, the corresponding key 42 of the transmission system is closed and the other key 43 is left open. The transmission system will now emit oscillations having a high frequency of 1,000,000 per second with a secondary frequency of 25,000 per second and will act in a well-known manner to energize the antenna 100 and to set up oscillations having a frequency of 25,000 per second in the corresponding secondary closed circuit 145 of the receiving system. These oscillations in the secondary circuit 145 will cause corresponding oscillations of 25,000 per second in the closed control circuit 152 which will be acted upon by the oscillations of either 24,000 per second or 26,000 per second produced by the corresponding local source of oscillations 217, thus setting up electrical beats in the closed circuit 152, having a frequency of 1,000 per second. The corresponding secondary detector 172 acts in a well-known manner to cause oscillations of a frequency of 1,000 cycles per second to be set up in the closed circuit 192, and these latter oscillations act to control the succeeding closed circuit 205 and cause the corresponding detector 208 to produce unidirectional pulsations of 1,000 per second in the circuit 209, 210 controlled thereby, which may be heard in the corresponding telephone 210.

When it is desired to control the telephone 200 of the receiving system shown in Fig. 2, the key 42 of the receiving system shown in Fig. 1 is left open, and the key 43 is closed, thus causing the transmission system to emit radiant oscillations having a frequency of 1,000,000 per second and a secondary frequency or periodic amplitude variations of 30,000 per second. This series of oscillations acts through the open, aerial circuit 100, the primary detector 120, the closed secondary circuit 143, the controlled secondary circuit 150, and the corresponding detectors 170 and 198 to control the telephone 200 under the influence of the electrical beats of 1,000 per second produced in the controlled secondary circuit 150 in a manner similar to that just described in connection with the control of the other telephone 210.

When it is desired to control both receiving telephones 200 and 210 simultaneously, both keys 42 and 43 of the transmission system are simultaneously closed, and the open,

aerial circuit 10 is thereby caused to emit high frequency oscillations of 1,000,000 per second having impressed thereon a secondary frequency or periodic amplitude variations of 20,000 per second. These oscillations will act as hereinbefore described through the receiving circuit 100, the primary detector 120, the corresponding secondary closed circuit 144, the corresponding closed circuit 151, and the corresponding secondary detector 171 to cause oscillations of 1,000 per second to be set up in the corresponding controlled circuit 191 under the influence of the beats of 1,000 per second set up in the closed secondary circuit 151 by the action of the corresponding local source of oscillations 216. The secondary circuit 191, consequently, simultaneously controls both of the closed circuits 195 and 205 to simultaneously operate the two telephones 200 and 210 as hereinbefore described.

For the purpose of rendering this system immune to the effects of disruptive, static discharges or powerful, forced interference to coils 178 and 179 of the closed circuits 190 and 191 are preferably disposed so that for simultaneous and equal currents in the circuits 190 and 191 the inductive effects on the common circuit 195 shall be equal and opposite and shall result in no net induced current in the circuit 195. Likewise, the coils 179 and 180 of the closed circuits 191 and 192 are so disposed that for simultaneous and equal currents in the circuits 191 and 192 the inductive effects on the common circuit 205 shall be equal and opposite and shall result in no net induced current in the circuit 205. This disposition of the coils 178, 179 and 180 will in no wise affect the regular operation of the system since in the course of the regular operation only one of these coils is energized at a time.

In the case, however, of disruptive, static discharges or powerful, forced interference, sudden and abrupt current fluctuations in the open aerial circuit 100 will be caused, which will in turn operate through the closed circuit 112 and the oscillation detector 120 causing similarly abrupt and sudden current fluctuations in the controlled circuit 135, 136, 137, 138. Under the influence of these abrupt and sudden current fluctuations, which will be either periodic or of a frequency far removed from the natural frequencies of the closed circuits 143, 144, and 145, the closed circuits 143, 144, and 145 will be equally stimulated, thus equally stimulating the circuits 150, 151, 152, the oscillation detectors 170, 171, 172, and the controlled circuits 190, 191, 192 and, through the balanced disposition of the coils 178, 179, 180 before mentioned, in no wise stimulating the circuits 195, 205 or the oscillation detectors 198, 208, or the telephones 200, 210. It is therefore evident that the

balanced arrangement of the coils 178, 179, 180 with respect to the circuits 195, 205 just described, will shield the final detectors 198, 208 and, consequently, the telephones 200, 210 from the undesired effects of static discharges or powerful forced interference.

From the foregoing it is thought to be evident that this invention provides a system whereby two operators may transmit simultaneously and independently any two desired messages and two other operators may simultaneously and independently receive these messages in a receiving system controlled by a single aerial circuit.

Although only a single form has been shown in which this invention may be embodied, it is to be understood that the invention is not limited to any specific construction but might be embodied in various systems without departing from the spirit of the invention or the scope of the appended claims.

Having thus fully described this invention, I claim:

1. A receiving system for electric oscillations, including an element tuned to a predetermined frequency, a plurality of secondary elements controlled by said first-mentioned element and tuned to a plurality of different frequencies respectively, local means for producing in each of said secondary elements respectively electrical beats having the same frequency in each of said elements, and a plurality of separately operative receiving devices arranged to be controlled by said elements respectively, each of said receiving devices being arranged to be controlled as a result of the action of the said beats in the corresponding secondary element.

2. A receiving system for radiant oscillations, including a primary element responsive to radiant oscillations and tuned to a predetermined frequency, a plurality of secondary elements controlled by said primary element and tuned to different frequencies respectively, separate, local means for producing electrical beats in said secondary elements, and a plurality of receiving devices arranged to be selectively controlled as a result of the action of said beats.

3. A receiving system for radiant energy comprising a primary receiving element responsive to radiant energy, a plurality of secondary elements tuned to different, super-audible frequencies respectively and arranged to be selectively controlled as a result of the action of said primary element, means for producing electrical beats in said secondary elements between locally-generated currents and currents of the different, super-audible frequencies to which the secondary elements are tuned and a plurality of receiving devices arranged to be selectively

tively controlled as a result of the action of said secondary elements.

4. A receiving system for radiant energy comprising an open, aerial circuit responsive to radiant energy and tuned to a predetermined frequency, three, secondary, closed, oscillatory circuits tuned to three, different, secondary frequencies respectively and arranged to be controlled as a result of the action of said open aerial circuit, three, closed, oscillatory circuits controlled by said secondary circuits respectively, local means for impressing oscillations on said controlled circuits respectively to produce electrical beats therein, and two, separately-operative receiving devices arranged to be selectively controlled as a result of the action of said beats in two of said controlled circuits respectively, and to be simultaneously controlled as a result of the action of said beats in the third one of said controlled circuits.

5. The method of transmitting energy which consists in producing a series of electrical oscillations, modifying said oscillations by selectively impressing thereon any one of three series of periodic variations having different frequencies respectively, selectively causing the operation of any one of three suitably tuned receiving elements as a result of said periodic variations respectively and causing the operation of two receiving devices either selectively as a result of the operation of two of the receiving elements or simultaneously as a result of the action of the third receiving element.

6. A receiving system for radiant oscillations, including a primary element responsive to radiant oscillations and tuned to a predetermined frequency, a plurality of secondary elements controlled by said primary element and tuned to different frequencies respectively, local means for producing electrical beats in said secondary elements, and a plurality of receiving devices arranged to be selectively controlled as a result of the action of said beats in certain of said controlled elements and to be simultaneously controlled as a result of the action of said beats in another of said controlled elements.

7. A receiving system for radiant oscillations, including a primary element responsive to radiant oscillations and tuned to a predetermined frequency, a secondary element controlled by said primary element, means for producing a single series of electrical beats in said secondary element, and a plurality of independent circuits adapted to control a plurality of receiving devices, said circuits being arranged to be simultaneously controlled as a result of the action of said single series of beats.

8. A receiving system for radiant oscillations, including means for receiving a plu-

- rality of series of periodic radiant impulses having different frequencies respectively, a plurality of receiving devices, and means including thermionic valve controlled elements tuned to said different frequencies respectively and interposed between said receiving means and said receiving devices for actuating said devices either selectively in accordance with a plurality of said series of impulses or simultaneously in response to a single one of said series of impulses.
9. A receiving system for radiant oscillations, including circuits tuned to a plurality of series of periodic, super-audible impulses having different frequencies respectively, a plurality of receiving devices and means interposed between said circuits and said receiving devices for operating said devices either selectively in accordance with a plurality of said series of impulses or simultaneously in response to a single one of said series of impulses.
10. A receiving system for radiant oscillations, including a circuit tuned to the frequency of a series of periodic super-audible impulses, a plurality of receiving circuits, a thermionic valve for separately controlling each of the receiving circuits and beat producing means interposed between said circuit and said thermionic valves adapted to produce a single series of beats, for operating said receiving devices in response to said series of beats.
11. In a system of telegraphy, a transmitting system comprising two telegraph keys and means selectively controlled thereby for generating electrical impulses of either of two different frequencies, said means being arranged to generate electrical impulses of a third frequency upon simultaneous operation of said keys, in combination with a receiving system including two receiving devices, means for separately controlling said receiving devices respectively in response to impulses of said two first-mentioned frequencies, and means for controlling said receiving devices simultaneously in response to impulses of said third frequency.
12. A transmitting system comprising a number of separately-operative, controlling elements, and means controlled thereby for selectively generating a larger number of series of impulses having different frequencies respectively, in combination with a receiving system having receiving devices equal in number to said controlling elements, means for separately controlling said receiving devices respectively in accordance with a plurality of said series of impulses, and means for operating a plurality of said receiving devices in accordance with a single series of said impulses.
13. A receiving system including two receiving devices, two receiving circuits tuned to two different frequencies respectively and arranged to control said devices respectively and a third circuit tuned to a third frequency and arranged to control both of said devices simultaneously.
14. A system for receiving high frequency oscillations having impressed thereon a plurality of series of periodic amplitude variations of different, super-audible frequencies, comprising a receiving circuit tuned to the frequency of said oscillations, secondary circuits controlled by the first-mentioned circuit and tuned respectively to the frequencies of said series of variations, a receiving device, a closed, oscillatory circuit controlling said device, and two circuits controlled respectively by said secondary circuits, each of said two circuits being arranged to control said closed, oscillatory circuit independently of the other and to oppose the other and substantially to counter-balance its effect on said closed, oscillatory circuit when both of said two circuits act simultaneously upon the closed, oscillatory circuit.
15. A receiving system including two receiving devices, two receiving circuits tuned to two different frequencies respectively and arranged to control said devices respectively and a third circuit tuned to a third frequency and arranged to control both of said devices simultaneously, the construction and arrangement being such that when all of said three circuits are energized substantially equally the effect of said third circuit upon each of said two devices will be opposed and substantially balanced by the effect of the corresponding one of said first mentioned two circuits.
16. A system for receiving high frequency oscillations, having impressed thereon a plurality of series of periodic, amplitude variations of different frequencies, comprising a receiving circuit tuned to the frequency of said oscillations, secondary circuits controlled by the first-mentioned circuit and tuned respectively to the frequencies of said series of variations, a receiving device, a control circuit therefor, two circuits separately controlled by said secondary circuits respectively and connected to the circuit of the receiving device to enable the circuit to be separately controlled by either of said two circuits, said two circuits being connected to the circuit of the receiving device in opposition to each other to neutralize their effect on the last-mentioned circuit when the two circuits act thereon simultaneously with equal effects.
17. A system for receiving high frequency oscillations having impressed thereon a plurality of series of periodic, amplitude variations of different, super-audible frequencies, comprising a receiving circuit

6
tuned to the frequency of said oscillations, secondary circuits controlled by the first-mentioned circuit and tuned respectively to the frequencies of said series of variations, 5 local means co-acting with said secondary circuits to produce beats of substantially equal frequencies in said circuits, a receiving device, a circuit for controlling the receiving device and two circuits tuned to the 10 frequency of said beats and separately controlled by said secondary circuits respectively, said two circuits being connected to the circuit of the receiving device to enable the last-mentioned circuit to be separately 15 controlled by either of said two circuits and said connections being oppositely arranged to neutralize the effect of the two circuits on the circuit of the receiving device when the two circuits act thereon simultaneously 20 with equal effects.

18. A system for electrical communication comprising a transmitter having a plurality of message controlling devices, a receiver comprising a plurality of receiving 25 circuits and means at the transmitter and receiver for causing one or a plurality of receiving circuits to be operated in response

to a single message depending upon the selection and the manner in which a single controlling device is operated in sending a 30 message.

19. A system for receiving radiant energy comprising a plurality of circuits tuned respectively to a plurality of series of super-audible impulses, two receiving devices, 35 means controlled by one of said circuits for operating one of said receiving devices independently of the other, and means controlled by another of said circuits for operating both of said receiving devices. 40

20. A system for electrical communications comprising a receiver including a plurality of receiving circuits, a transmitter, and means at the transmitter and receiver for causing one or a plurality of the receiving devices to be operated in response to a single message at the will of the operator of the transmitter, in response to the selection and operation of a single modulating 45 means. 50

This specification signed this 9th day of October, A. D. 1917.
